FIRE EXTINGUISHER

William Louis Roessner, Denver, Colo., assignor to
Bertha L. MacGregor, as trustee

Application February 23, 1939, Serial No. 257,866

6 Claims. (Cl. 169—26)

This invention relates to fire extinguishers, and particularly to automatic extinguishers in which a chemical such as carbon tetrachloride is employed as the extinguishing agent.

Heretofore, extinguishers of the character described have been provided with glass housings for the chemical and with fuse controlled hammers for breaking the glass and releasing the chemical. The main object of my invention is to increase the durability and to reduce the cost of such devices by substituting a metal container for the glass housing, and to provide means for dependably, efficiently and automatically puncturing the metal to release the contents of the container.

Another object is to construct the container and the puncturing means in such manner that the puncturing means is located and is operable within the space occupied by the container. This is a very important feature whereby the automatic operation of the device cannot be interfered with by objects which may have been placed adjacent to the extinguisher.

Another object is to produce an extinguisher in which the fire extinguishing chemical passes out of the container in streams, and preferably the streams gush toward each other, whereby the volatilization of the fluid and its fire extinguishing property are increased.

Another object is to provide means for filling, sealing and carrying the container in a simple and efficient manner.

The invention has produced a substantial saving in the cost of packing and shipping fire extinguishing devices, as well as in the initial cost. Breakage has also been avoided.

In the drawings:

Fig. 1 is a vertical sectional view of a fire extinguisher embodying my invention, taken in the plane of the line 1—1 of Fig. 2.

Fig. 2 is a bottom plan view of the extinguisher shown in Fig. 1.

Fig. 3 is an enlarged sectional view taken in the plane of the line 3—3 of Fig. 1.

Fig. 4 is a vertical sectional view, enlarged, taken in the plane of the line 4—4 of Fig. 1.

Fig. 5 is a perspective view of the fuse shown in Figs. 1 and 2.

Fig. 6 is a vertical sectional view of the lower portion of a modified form of extinguisher, taken in the plane of the line 6—6 of Fig. 7.

Fig. 7 is a bottom plan view of the extinguisher shown in Fig. 6.

Fig. 8 is a view similar to Fig. 6, showing an-

other modification, taken in the plane of the line 8—8 of Fig. 9.

Fig. 9 is a bottom plan view of the extinguisher shown in Fig. 8.

5 In that embodiment of the invention shown in Figs. 1 to 5, inclusive, the container 10 is preferably made of metal adapted to receive carbon tetrachloride or other fire extinguishing chemical. The container 10 is provided with a bottom wall 11 having a raised portion 12 connected to the bottom wall 11 by a vertical wall 13, forming a bottom opening recess in the container bottom.

In the top 14 of the container, a small hole is 15 provided for filling the container. The container must be sealed without permitting any solder to contaminate the chemical, and for this purpose I provide a plate 15, having a raised portion in the form of a rib, which is placed over the opening in the top 14 and soldered to the top at 15'. A handle 16 made of spring metal has its free ends inserted under the rib portion of the plate 15, and provides means for carrying the device or hanging it on a hook.

20 The device is provided with thermo-controlled, automatic puncturing means for the purpose of releasing the container contents. Said means is located in the recess formed in the bottom of the container and preferably entirely within the space occupied by the container. The puncturing means comprises a tubular, open ended, horizontally disposed housing 17, slotted longitudinally at the bottom as indicated at 18, secured to the container wall 12 by any suitable means indicated at 19.

25 Within the housing 17 are two oppositely facing, pointed puncturing members 20, 20, longitudinally and centrally bored at 21, each provided with a depending retaining tongue 22. The tongues 22 engage a thermo-responsive fuse 23. Between the puncturing members 20 is a compressed coiled spring 24 which is powerful enough to force the puncturing members 20 to move in opposite directions and to puncture the vertical wall 13 of the container 10, at opposite 30 sides of the recessed bottom, when the fuse becomes affected by heat and releases the retaining tongues 22, but normally the fuse 23 and tongues 22 remain in the position shown, prevent expansion of the spring 24, and hold the parts inoperatively.

35 The fuse 23 may be constructed in a variety of ways, but as shown, it comprises two narrow, thin strips 25 of readily formable metal, such as brass, parallel to each other except where they engage opposite sides of a pair of short tubular retain-

ers 26. The strips 25 are soldered together and to the retainers 26, by solder 27, the latter being spaced from each other in the assembled fuse so as to engage the outer surfaces of the tongues 22, as shown in Figs. 1 and 2, and prevent expansion of the spring 24.

The fuse 23 is constructed so that the solder 27 will melt at a predetermined temperature, say 160° F., whereupon the retainers 26 separate from the strips 25, the tongues 22 are released, and the puncturing members 20 move forcefully in opposite directions, under influence of the expansive power of the spring 24, and puncture the wall 13. The fluid in the container 10 passes out in streams through the bore 21 of the members 20 and the openings 18 in the housing 17. Thus the fire extinguishing chemical is efficiently and speedily released from its container.

In Figs. 6 and 7, the container walls 10, 11, 12 and 13 are formed as heretofore described, but the puncturing device comprises a pivotally mounted arm 30 arranged to swing in a horizontal plane on the pivot 31. The arm 30 is tubular or U-shaped, as desired, and has two pointed, tubular puncturing members 32 projecting from one side. The arm 30 is spring pressed at 33, and normally retained in the full line position of Fig. 7 by a fuse 34. The puncturing members 32 aperture the wall 13 as indicated by the dotted lines of Fig. 7, when the fuse 34 has been affected by heat and has released the arm 30. Said members 32 and arm 30 serve as conduits for the fluid when the container 10 has been punctured by the sharp ends of the members 32.

The construction shown in Figs. 8 and 9 comprises two arms 35, 36, mounted in different horizontal planes on a pivot pin 37, and spring pressed by springs 38, 39, to swing in opposite directions when the fuses 40, 41 are affected by heat and release the arms 35, 36. The arms 35, 36 are provided with pointed, hollow puncturing members 42, 43, respectively, which puncture the wall 13 at opposite sides of the recess in the bottom of the container 10.

Changes may be made in details of construction without departing from the scope of my invention. For example, the member 17 which supports the puncturing means 20 in the construction shown in Figs. 1 to 4, inclusive, may be round, oval or square in cross section, and it may be reduced in size and fit within the spring 24 and the bore 21 of the puncturing members 20, without interfering with the automatic movement of said members 20 when released by disintegration of the fuse.

In the constructions shown in Figs. 1 to 4 and 8 and 9, the streams of released chemicals definitely meet each other, and thus the solid body of fluid is broken and diffused into numerous, tiny globules. In the construction shown in Figs. 6 and 7, the released streams strike the vertical wall 13 of the container and are likewise diffused. Thus volatilization is rapidly and efficiently effected. If the chemical is not diffused, the fire extinguishing blanket of volatized fluid forms much more slowly, and some of the chemical might not volatilize at all. This objection is overcome by my invention.

I claim:

1. A fire extinguisher comprising a container having a recess formed in one of its walls, puncturing means mounted in said recess, means for actuating the puncturing means, and thermo-responsive retaining means for rendering the puncturing means inoperative, said retaining means comprising a pair of easily formable metal strips, a pair of tubular retainers between said strips and solder connecting the strips to each other and to the retainers, said puncturing means being engaged by said retaining means between said tubular retainers.

15 2. A fire extinguisher comprising a container made of puncturable but non-shatterable material, puncturing means mounted on the container, means for actuating the puncturing means, and thermo-responsive retaining means for rendering the puncturing means inoperative, said retaining means comprising a pair of easily formable metal strips, a pair of tubular retainers between said strips and solder connecting the strips to each other and to the retainers, said puncturing means being engaged by said retaining means between said tubular retainers.

25 3. A fire extinguisher comprising a container having a recess formed in one of its walls, puncturing means mounted and operable in said recess, thermo-responsive retaining means for rendering the puncturing means inoperative until a predetermined temperature has been reached and then automatically releasing the puncturing means, and means for actuating the puncturing means when said retaining means has been released, said puncturing means comprising 30 a pair of aligned, hollow, pointed members, a coiled spring between said members, and means on the puncturing members engaged by said retaining means.

40 4. A fire extinguisher consisting essentially of a non-shatterable container holding fire extinguishing liquid, said container having an open bottom recess formed in one of its walls, means for puncturing the container mounted directly on said container and operable entirely within the recess, said puncturing means being located to puncture the vertical wall of the recess, thereby releasing the container contents in horizontally directed streams, and thermo-responsive retaining means connected to the puncturing means for controlling said means.

45 5. A fire extinguisher consisting essentially of a non-shatterable, unitary container having a recess formed in one of its walls, automatically operable puncturing means mounted in and operable within said recess for puncturing the recess wall, and thermo-responsive means also mounted within the recess for normally restraining said puncturing means.

60 6. A fire extinguisher consisting essentially of a non-shatterable, unitary container having a recess formed in one of its walls, automatically operable puncturing means mounted in and operable within said recess for puncturing the recess wall at spaced apart points, and thermo-responsive means also mounted within the recess for normally restraining said puncturing means.

WILLIAM LOUIS ROESSNER.
